HYDROCARBON CONVERSION

Charles L. Thomas, Chicago, Ill., assignor to Universal Oil Products Company, Chicago, Ill., a corporation of Delaware

Application June 30, 1941, Serial No. 400,373

4 Claims. (Cl. 196—52)

The present invention relates to the conversion of petroleum oils and deals more specifically with improvements in cracking such oils in the presence of solid catalysts.

This invention is concerned principally with the type of process which comprises passing oil vapors over a fixed bed of catalyst in a reaction zone at the desired processing conditions and periodically interrupting the flow of hydrocarbons to regenerate the catalyst. In this type of operation it is important to control the conversion per-pass to obtain the optimum yield of gasoline from the charging stock. This conversion per pass will be defined as the weight percent of charging stock converted to gasoline and gas during the passage of the oil through the reaction zone. The amount of conversion of a particular hydrocarbon oil realized in a catalytic cracking reaction is dependent upon the catalyst activity, the space velocity of the hydrocarbon oil over the catalyst, and the temperature and pressure at which the reaction is occurring.

By varying any one or more of these factors the conversion per pass can be changed. The conversion per pass attended by any set method of operation will affect the economic feasibility of the process. For instance, if too high a conversion per pass were attained, large amounts of undesirable coke and light gases would be formed, tending to decrease the overall gasoline production. On the other hand, if too low a conversion per pass is maintained, the yield of desirable product formed during the processing period is too low, necessitating the reheating and recycling of excessive amounts of unconverted material which will considerably increase the expenditures necessary to carry out the cracking process. Therefore, it is necessary to determine the optimum conversion per pass desired which will give the maximum yield of desirable products without excessive coke deposition and gas formation and which will not entail the reheating and recirculating of large amounts of unconverted materials. It must be understood that this optimum yield will vary with different types of charging stocks and catalyst used but will usually be of the order of 25 to 50%.

It has been found when charging a hydrocarbon oil over a fresh or reactivated bed of catalyst in a cyclic operation that the conversion in the first portion of the period is very high and tapers off as the processing period length increases. It has also been found that the carbon deposition during this initial period of high catalyst activity is

excessively high, thereby greatly decreasing the catalyst activity.

It can readily be seen that during the initial part of the processing period when the catalyst is very active the percentage of charging oil converted to undesirable products such as coke and gas will be high. Also as the catalyst activity decreases, due to fouling of the catalyst with carbonaceous materials, the amount of conversion decreases, thereby necessitating the recycling of large amounts of unconverted materials.

The present invention discloses a process whereby an optimum conversion per pass can be maintained substantially constant throughout the entire processing period, thereby considerably decreasing the percentage of charging stock being converted to coke and gas during the first portion of the period and the amounts of unconverted materials which are to be recycled back to the process. It has been pointed out that the factors influencing the conversion per pass of a particular hydrocarbon oil are the processing temperature, space velocity and catalyst activity. It has also been pointed out that the catalyst activity decreases as the processing period length increases. Therefore, the present invention provides methods of varying the processing temperatures and space velocity to compensate for the loss in activity of the catalyst during the processing period, thereby maintaining a substantially constant conversion per pass throughout the entire processing period.

In one specific embodiment the present invention comprises a process for the catalytic conversion of hydrocarbon oil, contacting said hydrocarbon oil with a cracking catalyst under processing conditions which will vary simultaneously and dependently to compensate for the loss of catalyst activity due to the fouling of the catalyst by the deposition of carbonaceous material upon said catalyst, thereby effecting a substantially constant conversion per pass during the processing period.

Figs. 1, 2, and 3 of the accompanying drawing diagrammatically illustrate three separate arrangements of apparatus in which the methods and objects of this invention can be accomplished, but do not necessarily limit the invention to the use of such methods or apparatus.

Referring to Fig. 1, charging oil, for example, a Pennsylvania gas oil, is introduced from line 1 into pump 2 which discharges through valve 3 into heating coil 4 in furnace 5 where it is raised to a temperature within the range of 850 to 1100° F. The heated oil leaves the furnace through

line 6 and is split into two streams, passing through either line 7 or 8 containing valves 9 and 10. At the start of the processing period valve 10 is closed and the entire stream of hydrocarbon oil passes over the catalyst. The flow of oil is determined by the conversion per pass permissible without converting excessive amounts of the charging stock to undesirable products such as coke and gas. As the processing period continues with a subsequent decrease in catalyst activity due to carbon deposition, valve 10 is opened to decrease the amount of oil flowing to reactor 11. This decrease in flow is regulated to increase the time of contact between the hydrocarbon oil and the catalyst, thereby compensating for the reduction in catalyst activity and enabling the maintenance of a substantially constant conversion per pass throughout the entire processing period. The oil being diverted from the reactor may be used for heat exchange or any other suitable application. The reactants leaving reactor 11 pass through line 12 containing valve 13 to the usual fractionating and stabilizing equipment. The unconverted material separated from the gasoline boiling range and lighter hydrocarbons may be recirculated back to the process.

Referring to Fig. 2, the charging stock (stream A) is introduced through line 14 to pump 15 which discharges through valve 16 into heating coil 17 in furnace 18 where it is heated to a temperature between 500 and 800° F. The same charging stock (stream B) is introduced into line 21 to pump 22 which discharges through valve 23 into heating coil 24 in furnace 25 where it is raised to a temperature within the range of 850 to 1100° F. Stream A leaves heating coil 17 through line 19 containing valve 20 and combines with stream B, passing through line 26 containing valve 27. The two streams are combined in such proportions as to produce the desired temperature and space velocity in the reaction zone which will enable producing an optimum yield of gasoline without converting a large percentage of the charging stock to coke and gas. The combined streams pass through line 30 containing valve 31 into reactor 32. As the processing period continues the catalyst activity decreases due to fouling of the catalyst surfaces by carbonaceous materials. In order to compensate for this loss in catalyst activity, part of stream A is continuously being diverted from the flow to the reactors. The diverted portions pass through line 28 containing valve 29 and may be used in a heat exchange system or may be sent to an insulated storage vessel so that the variable use of stream A will not introduce any heating problems. The elimination of part of the colder stream decreases the amount of oil being passed to the reactor and increases the temperature of said oil. The effect of the decreased space velocity and increased processing temperature can be regulated to maintain a constant conversion per pass throughout the entire processing period. The reactants leaving reactor 32 through line 33 containing valve 34 are sent to the usual fractionating and stabilizing systems. The unconverted or partially converted hydrocarbons are separated from the gasoline boiling range and lighter hydrocarbons and may be recycled back to the process.

In Figs. 1 and 2 only one reactor is shown; however, in order that the operation may be made continuous, it is preferred that at least two reactors be employed so that the flow of hydrocarbon

reactants may be alternately switched from one reactor to the other, and in such case the catalyst in the reactor not in use is subjected to regeneration in the conventional manner.

In Fig. 3 the method is shown in which the objects of the invention can be accomplished using a multiple reactor system. To further illustrate the invention, let it be assumed that the process is operated on the cyclic operations of the following table: It must be understood that the cycle presented herein to be used as an illustration does not place undue limitation on the process, since many variations of the presented cycle can be used which will fall under the broad scope of this invention. The letter R is used to distinguish the catalyst containers being reactivated and the letters A and B to the charge streams. A complete cycle is considered to be 360°.

20	Reactor No.			
	55	56	57	58
25 Time of cycle:				
0-90°	A+1/2B	1/2B	R	R
90-180°	1/2B	R	R	A+1/2B
180-270°	R	R	A+1/2B	1/2B
270-360°	R	A+1/2B	1/2B	R

Referring to the drawing, the charging stock is introduced in two separate streams to heating coils 38 and 44. Stream A enters through line 35 into pump 36 which discharges through valve 37 into heating coil 38 in furnace 39 where it is heated to a temperature within the range of 500 to 800° F. and leaves the heating coil through line 40. Stream B enters through line 41 into pump 42 which discharges through valve 43 into heating coil 44 in furnace 45 where it is heated to a temperature within the range of 850 to 1100° F. and leaves the heating coil through line 46.

According to the cycle of the foregoing table, reactor 55 has just been put on stream and reactor 56 has been processing for some time. Since the catalyst in reactor 55 has just been freshly regenerated, it is in a highly active state. To avoid a high conversion per pass and the conversion of a large percentage of the charging stock to coke and gas, a larger volume of hydrocarbon vapors at a lower temperature is passed through the reactor, thereby increasing the space velocity of the hydrocarbon oil over the catalyst.

In the present case being illustrated, all of stream A will pass through valve 47 and combine with about one-half of stream B passing through valve 51, and the combined feed will enter catalyst reactor 55. The remainder of stream B will enter reactor 56 through valve 52. Since the catalyst activity in reactor 56 has been decreased by the carbon deposition incurred during the previous part of the processing period, the hydrocarbon oil will be passed through the reactor at a lower rate and a higher temperature, compensating for the loss in catalyst activity and maintaining a substantially constant conversion per pass. Reactors 57 and 58 are in the process of being regenerated. Regeneration in reactor 57 has just been started, while the regeneration in reactor 58 is nearing completion. The cycle is continued in accordance with the illustrative example presented with the hydrocarbon oil passing through lines 40 and 46, being introduced to any one or more of reactors 55 and 58, inclusive, through valves 47 to 54, inclusive.

It will be noted that the above arrangement

calls for an increased flow of oil at a lower temperature over the freshly regenerated catalyst and that the flow of oil is decreased and the temperature increased after a part of the on-stream time has elapsed. This arrangement takes advantage of the high initial activity of the catalyst and decreases the per cent of charging oil converted to gas and coke. A substantially constant optimum conversion per pass is obtained by varying the space velocity and processing temperatures to compensate for decreases in the catalyst activity during the processing period. In the drawing herein attached no regenerating equipment has been included. The regeneration may be carried out in the usual manner. The reactors may be manifolded so that the regenerating gases may be introduced to any one or more of the reactors. A short purge period with steam or substantially oxygen-free gases will be used to remove the hydrocarbon vapors before burning off the carbonaceous materials from the catalyst with oxygen or oxygen-containing gases.

The reactors illustrated in Figs. 1, 2, and 3 may comprise, for example, a conversion zone of the heat exchanger type wherein the catalyst is contained in a plurality of elongated tubular elements of relatively small diameter, provisions being made for passing some suitable heat convective fluid such as combustion gases in indirect heat exchange relationship with said tubular elements to supply heat to the reactants during conversion and to cool the catalyst and regenerating gases during regeneration. These reactors, on the other hand, may comprise cylindrical vessels containing one or a plurality of beds of catalytic material, said vessels being insulated to reduce radiation losses therefrom so that the conversion reaction may be accomplished substantially adiabatically.

Catalysts which have been found to be effective in the cracking of hydrocarbon vapors may comprise, for example, powder, pellets, or granules containing synthetically prepared, purified silica or other siliceous and refractory materials composed with one or more of the compounds selected from the group consisting of alumina, zirconia, magnesia and thoria. In addition, hydrosilicates of alumina, acid treated clays or the like have also been found to be effective in the cracking treatment of hydrocarbon vapors. Although the catalysts recited are generally considered to be the preferred catalysts their use is not to be construed as a limiting feature, for various other catalysts well known to those in the art may be employed in the broad scope of the invention.

The conversion products leave the reactors in Fig. 3 through lines 59 to 62, inclusive, containing valves 63 to 66, inclusive, depending upon which reactors are being processed, passing through the manifold line 67 into fractionator 68. The cracked products are fractionated within tower 68 and the unconverted materials withdrawn through line 71 containing valve 72. The unconverted materials may be recycled back to the process, thermally cracked, or sent to storage. The gasoline and gas withdrawn through line 69 containing valve 70 are passed through the usual condensing and stabilizing equipment and the desired products sent to storage.

Although in the previous examples the charging stocks used were of the same type of oil, it does not follow that this is necessary in the present invention. There are a number of variations which are within the scope of this invention. The individual streams of oil may be virgin stock having the same boiling range or may consist of

virgin stocks having different boiling ranges. One stream may be made up in part or entirely of the recycle from the catalytic cracking reaction or it may be made up entirely or in part of a thermally cracked gas oil. The process as disclosed is also particularly adaptable to using stocks having different susceptibilities to catalytic cracking and/or different carbon forming tendencies. These oils may be used as indicated above by charging one oil and then the other, charging the most reactive or worst carbon forming oil only in the last half of the processing period.

The method illustrated in Fig. 1 can also be applied to Fig. 3. The oil may be heated to the desired temperature and split into two streams as in Fig. 1. The decrease in catalyst activity can be compensated by the decreased volume of oil flowing to the reactors. It also follows that the invention is not limited to the number of reactors which can be used in the system.

Example I

A Mid-Continent paraffin distillate having an A. P. I. gravity of 32.3 was heated to a temperature of 950° F. and passed over a composite cracking catalyst comprising silica, alumina, and zirconia under atmospheric pressure.

The variations in space velocity had been determined from previous experiments and the space velocity was varied accordingly thereby, maintaining a constant conversion of 27.7% by weight of the charge throughout the processing period. The yields were 21.6% gasoline, 6.1% gas and 0.45% carbon.

When operating under the same temperature, but at a constant space velocity of 2.4, thereby obtaining the same average conversion, the gasoline yield was 20.8%, gas 6.9% and carbon 0.60%.

When comparing the above data, it is evident that the operation in which the space velocity was varied to maintain a constant conversion has definite advantages over the standard process. Not only is the gasoline yield 3.8% greater but the carbon deposition is about 25% less.

This decrease in carbon deposition is very important, since it considerably simplifies the regeneration of the catalyst.

Example II

A 32° A. P. I. gravity Mid-Continent paraffin distillate was catalytically cracked by passing the heated vapors over a catalyst comprising alumina, silica, and zirconia at a constant space velocity of 2. The temperature was maintained at 955° F. throughout the processing period. The conversion was 33.4% by weight of the original charge. The yields were gasoline 22.9%, recycle stock 64.4%, gas 10.8% and coke 1.9%.

The same charging stock was passed over the same type of catalyst at a constant space velocity with the temperature being varied at a predetermined rate from 875-970° F. to maintain a constant conversion of 33.4%.

The distribution of products was much better in the second test, the yields being gasoline 24.0%, gas 9.6%, recycle stock 64.6% and coke 1.8%.

The gasoline to gas relationship was improved considerably in the second test while the carbon deposition was slightly lower.

The novelty and utility of the present invention have been shown by the preceding specification and examples, although neither section is intended to unduly limit its generally broad scope.

I claim as my invention:

1. In the process of catalytically converting hydrocarbons wherein the hydrocarbon reactants are heated to reaction temperature and passed in contact with an active catalyst capable of promoting the reaction, the activity of said catalyst decreasing as the processing period progresses, the catalyst being periodically regenerated to restore its activity, and the operation being made continuous by employing a plurality of reaction zones in which the catalyst is disposed, each of said reaction zones being alternately processed and regenerated and wherein the conversion reaction is conducted simultaneously in at least two of said reaction zones and the time of introduction of the hydrocarbon reactants is so regulated that said reaction zones are in different stages of processing, the improvement which comprises, heating separate streams of the hydrocarbon reactants each to a different temperature, supplying to the reaction zones as the conversion reaction progresses therein varying portions of said separately heated streams, said portions being regulated to maintain a high space velocity and relatively low temperature in the reaction zone wherein the catalyst activity is relatively high, and to maintain a lower space velocity and high temperature in the reaction zone wherein the catalyst activity is relatively low.

2. In the process of catalytically cracking hydrocarbons wherein the hydrocarbon reactants are heated to reaction temperature and passed in contact with an active catalyst capable of promoting the reaction, the activity of said catalyst decreasing as the processing period progresses, the catalyst being periodically regenerated to restore its activity, and the operation being made continuous by employing a plurality of reaction zones in which the catalyst is disposed, each of said reaction zones being alternately processed and regenerated and wherein the conversion reaction is conducted simultaneously in at least two of said reaction zones and the time of introduction of the hydrocarbon reactants is so regulated that said reaction zones are in different stages of processing, the improvement which comprises, heating separate streams of the hydrocarbon reactants each to a different temperature, supplying to the reaction zones as the conversion reaction progresses therein varying portions of said separately heated streams, said portions being regulated to maintain a high space velocity and relatively low temperature in the reaction zone wherein the catalyst activity is relatively high and to maintain a lower space velocity and high temperature in the reaction zone wherein the catalyst activity is relatively low.

3. In a process of catalytically converting hydrocarbons wherein the hydrocarbon reactants are heated to reaction temperature and passed in contact with an active catalyst capable of promoting the reaction, the activity of said catalyst decreasing as the processing period progresses, the catalyst being periodically regenerated to restore its activity, and the operation being made continuous by employing a plurality of reaction zones in which the catalyst is disposed, each of said reaction zones being alternately processed and regenerated and wherein the conversion re-

action is conducted simultaneously in at least two of said reaction zones and the time of introduction of the hydrocarbon reactants is so regulated that said reaction zones are in different stages of processing, the method which comprises continuously supplying to the process a first hydrocarbon reactant stream of relatively high temperature and a second hydrocarbon reactant stream of lower temperature, introducing said second stream and a portion of said first stream into one of said reaction zones containing catalyst of relatively high activity, simultaneously introducing the remainder of said first stream to another of the reaction zones containing catalyst of lower activity than said one reaction zone, the amount of said remainder being such as to maintain in said other zone a ratio of conversion products to reactants per pass substantially equal to that in said one zone, continuing the introduction of reactants to said zones as aforesaid until the activity of the catalyst therein has decreased substantially and thereafter diverting said second stream and said portion of the first stream from said one zone into a third reaction zone containing freshly regenerated catalyst while diverting said remainder of the first stream from said other zone into said one zone.

4. In the process of catalytically converting hydrocarbons wherein the hydrocarbon reactants are heated to reaction temperature and passed in contact with an active catalyst capable of promoting the reaction, the activity of said catalyst decreasing as the processing period progresses, the catalyst being periodically regenerated to restore its activity, and the operation being made continuous by employing a plurality of reaction zones in which the catalyst is disposed, each of said reaction zones being alternately processed and regenerated and wherein the conversion reaction is conducted simultaneously in at least two of said reaction zones and the time of introduction of the hydrocarbon reactants is so regulated that said reaction zones are in different stages of processing, the method which comprises continuously supplying to the process a first hydrocarbon reactant stream of relatively high temperature and a second hydrocarbon reactant stream of lower temperature, introducing said second stream and a portion of said first stream into one of said reaction zones containing catalyst of relatively high activity, simultaneously introducing another portion of said first stream to another of the reaction zones containing catalyst of lower activity than said one reaction zone, the amount of said other portion being such as to maintain in said other zone a ratio of conversion products to reactants per pass substantially equal to that in said one zone, continuing the introduction of reactants to said zones as aforesaid until the activity of the catalyst therein has decreased substantially, and thereafter diverting said second stream from said one zone into a third reaction zone containing freshly regenerated catalyst while diverting said other portion of the first stream from said other zone into said third zone and continuing the introduction of the first-mentioned portion of the first stream into said one zone.
